United States Patent Office

Des. 181,591
Patented Dec. 3, 1957

181,591

SHOE SHINING STAND

Frank G. Lee, Fayetteville, Ark.

Application December 3, 1956, Serial No. 44,028

Term of patent 14 years

(Cl. D9—2)

Fig. 1

Fig. 2

Fig. 3

Fig. 4

Fig. 5

Fig. 1 is a view in perspective of a shoe shining stand, showing my new design,

Fig. 2 is a front elevational view of the stand,

Fig. 3 is a top plan view of the stand,

Fig. 4 is a side elevational view of the stand, and

Fig. 5 is a rear elevational view of the stand.

I claim:

The ornamental design for a shoe shining stand, as shown.
